YARN SHEET CUTTING MECHANISM

Eric W. Strack, Amsterdam, N. Y., assignor to
Bigelow-Sanford Carpet Co., Inc., Thompson-
ville, Conn., a corporation of Massachusetts

Application October 28, 1932. Serial No. 639,998

5 Claims. (Cl. 28—55.5)

This invention relates to the manufacture of carpets and rugs, and is more particularly directed to mechanism for cutting a series of yarns or a yarn sheet when the cutting instrumentalities are constituted as motor driven cutting members.

In weaving Axminster and like carpets and rugs, the pile forming tufts are derived from spools, each of which contains a series of yarns, either of the same or different color, wound side by side in a setting frame. When the requisite length of yarns have been wound upon a spool, the series of yarns, which constitutes a yarn sheet, are cut between the source of supply and the spool, and the latter is then mounted on a tube frame having a series of small tubes through each of which projects the end of one of the yarns extended from the wound spool.

It has been the common practice heretofore to cut the series of yarns or yarn sheet by a slow hand operation, with the result that the ends of the yarns extending from the wound spool have been uneven, and necessitated a trimming operation after the removal of the wound spool from the setting frame with consequent waste of expensive yarn.

One of the objects of the present invention is to provide a cutting mechanism for a series of yarns or yarn sheet so contrived that it will cut the yarn sheet transversely in a straight line, thus eliminating waste.

Another object of the invention is to provide for an expeditious action of the cutting operation by motor driven cutters mounted and supported for bodily movement across the yarn sheet, thereby economizing in time and labor of the machine attendant.

In accordance with the present embodiment of the invention the motor driven cutters are supported for bodily movement transversely of the yarn sheet between the source of yarn supply and the spool on which the yarns are wound, so that by a single traverse of the motor driven cutters from one to the other edge of the yarn sheet, the yarns are quickly cut in a straight line and the wound spool is at once ready to be associated with its tube frame.

The invention and novel features thereof will best be made clear from the following description and accompanying drawings of a setting frame provided with the invention.

In the drawings:—

Fig. 1 is a sectional side view of a conventional or standard setting frame provided with the

present invention and showing the yarn line when the spool is being "over wound";

Fig. 2 is a view similar to that of Fig. 1 showing the yarn line when the spool is "under wound" and also illustrating a wound spool with the yarns positioned for cutting;

Fig. 3 is an enlarged side elevation with parts broken away of a motor driven cutting mechanism;

Fig. 4 is a top or plan view with parts broken away showing the motor driven cutting mechanism; and

Fig. 5 is a perspective view showing the parts positioned for cutting when the spool has been "over wound".

The conventional or standard setting frame is provided with driving mechanism for rotating the spool to be wound and drawing the series of yarns from a convenient source of supply. Only so much of the setting frame is illustrated as is necessary to make clear the association of the present invention therewith.

Mounted upon the supporting frame work 1 of the setting frame are the driving rolls 2 and 3 which constitute in connection with the presser roll 4 one good form of winding mechanism for rotating the spool to be wound.

When the spool has been supplied with the desired length of yarns wound thereon side by side the yarn sheet is to be cut in order that the wound spool may be transferred to the tube frame for drawing the ends of the yarns singly through individual tubes, and one of the important features of the present invention consists in motor driven cutting mechanism so associated with the setting frame that by a single traverse of the motor driven cutting mechanism transversely of the yarn sheet, the latter will be cut on a straight line and the ends of the cut yarn leading from the spool be all of even length and ready to be drawn through the tubes of the tube frame.

In accordance with the present invention the motor driven cutting mechanism is constituted as a motor driven shears mounted and guided for movement transversely of the setting frame in a straight line between the wound spool and the source of the yarn supply.

Pivotaly mounted upon the supporting frame 1 are the side arms 5 which may have their pivotal association with the supporting frame at a point 6, and each side arm is provided with a seat 7 for the support of a wound spool when it is transferred from its winding position to the seats of the side arms. As more clearly illus-

trated in Fig. 5 the seats 7 of the side arms engage the wound spool preferably near the end portions thereof so that the wound yarn is engaged by the seats and thus prevented from accidental unwinding.

5 Each of the side arms is provided with an end support 8 preferably at an angle to the longitudinal length of the side arms, so that the seat 7 extends backwardly slightly and gives effective support to the wound spool. The seat 7 may be formed integral with the arms, but as herein shown they are separately formed and secured to the side arms by appropriate securing means, as for instance, the bolts 9.

10 15 Extending transversely of the setting frame is a guide bar 10 positioned between the seat 7 for the wound spool and the winding mechanism. The guide bar 10 may be appropriately secured in the desired position preferably close or adjacent to the seat 7 by the bolts 9 which secure the seat 7 to the side arms.

20 25 Mounted for movement transversely between the side arms 5 on the guide bar 10 is a slide 11 having its end portions 12 turned back of the guide bar, as clearly indicated in Figs. 1 and 2 to maintain the slide 11 in free sliding engagement with the guide bar 10, the construction being such that the slide 11 may be freely moved transversely of the setting frame and across the yarn sheet between the side arms 5.

30 35 Secured to the slide 11 as by means of a bracket 13, Fig. 5, is the motor driven cutting mechanism 14 having a handle 32 such that when the yarn is to be cut by the motor driven cutters the cutting mechanism and slide may be moved transversely of the yarn sheet and effect a straight line cut.

40 The cutting mechanism in the present embodiment of the invention is constituted by motor driven shears formed of the fixed member 16 and the movable member 17 pivoted together at 18, as indicated more clearly in Figs. 3 and 4.

45 50 The fixed member 16 of the motor driven shears has a frontwardly extending portion 19 fixedly secured to a plate 20 as by means of screws or like securing means 21, thus the member 16 of the shears is held stationary as the motor driven shears are moved transversely of the setting frame substantially as hereinbefore described.

55 60 The movable member 17 of the shears has an extended portion 22 connected at 23 to a link 24 which is itself connected to a crank disk 25 mounted upon and fixed to the motor driven shaft 26, the construction being such that when the motor driven shaft 26 is rotated the movable member of the shears will be rapidly operated and in connection with the fixed cutting member 16 serve to cut the series of yarns or yarn sheet.

65 The motor may be of any usual type and as more clearly illustrated in Fig. 4 the motor 27 is of the electric type and secured to the fixed plate 20 by suitable means, such as the screws 28.

70 75 The motor and its associated parts are preferably enclosed by a casing 29 and to the casing 29 is secured the hand bracket 30 by means of a screw 31, so that handle 32 for moving the motor driven shears and slide transversely of the machine may be in convenient position for operation. Mounted upon the hand bracket 30 is an electric switch 33, best shown in Figs. 3 and 4, so located with respect to the handle 32 as to be in convenient position for manipulation by the machine attendant.

Secured to the binding posts 34 and 35 are the 75 electric wires 36 and 37 which as more clearly

shown in Fig. 4 connect with the terminals 38 and 39 of the electric motor 27, whereby on manipulation of the electric switch 33 by the finger of the machine attendant the motor is started or stopped as circumstances dictate.

80 The side arms 5, Fig. 1, are normally under the influence of springs 40 which act during the winding operation to maintain the side arms in an upright position as indicated in Fig. 1 and in order to limit the movement of the side arms 5 under the stress of the spring suitable stops 41 may be utilized.

85 90 When the winding spool has been "over wound" as indicated at 42, Fig. 1, the lead of the series of threads from the source of supply to the filled or wound spool is such the "over wound" spool 42 may be transferred to the seat 7 and thereupon, in order to place the yarn sheet in position for cutting, the side arms 5 may be turned downwardly against a stop 41^x into the dotted line position, Fig. 1, so that the lead of the yarn sheet, as shown by dotted lines, Fig. 1, is directly through the path of the motor driven shears. The parts being in the position stated with the "over wound" spool in the seat 7, dotted lines, Fig. 1, the motor 100 driven shears and slide may be transversely moved across the machine, as indicated in Figs. 1 and 5, thereby effecting a cut of the yarn sheet rapidly and in a straight line.

95 100 105 When the spool is "under wound", as indicated in Fig. 2 and the wound spool is transferred to the seat 7, a fresh spool 43, Fig. 2, may be placed in the loop or bight of the yarn sheet *a* and the presser roll 4 be permitted to drop to its lower winding position whereupon the lead of the yarn from the fresh spool to the wound spool supported in the seats 7 is positioned for the cutting operation without turning the arms 5 to their lowered position as in the case of cutting the yarn sheet when the spool has been "over wound". This position of parts is well indicated in Fig. 2 and in order to direct the yarn sheet for the "under winding" operation a guide bar 44 extends transversely of the machine and over this passes the yarn sheet *a*, then downwardly and under the 110 fresh spool 43, then upwardly to the right of the presser roll 4 and to the wound spool supported in the seats 7 of the side arms, and it will be noted that in this position of parts the yarn passes over the guide bar 10 and is positioned in the path 115 of the motor driven shears.

115 120 125 From the construction described it will be apparent that the present invention provides a motor driven cutting mechanism or shears supported for sliding movement transversely of the machine between the side arms and across the yarn sheet whether the spool be "over wound" or "under wound" and since the cutting mechanism is supported during its movement transversely of the machine the attendant has not the duty of supporting the rather heavy motor driven cutting mechanism but merely slides it manually from one side of the machine to the other.

130 135 140 What is claimed is:—

140 145 150 1 In a setting frame for winding a series of yarns side by side on a spool, the combination of winding mechanism for rotating the spool, arms pivotally mounted on the frame and having supporting seats for a wound spool, a guide bar secured in fixed relation to the arms between the supporting seats for the wound spool and the pivotal connection of the arms to the frame, so that the guide bar moves with the arms as they are turned about their pivotal supports and motor driven shears mounted on the guide bar

- for movement with the side arms and for bodily sliding movement thereon transversely of the series of yarns to cut the series of yarns in a straight line as the motor driven shears are moved across the series of yarns. 5
2. In a setting frame, means for winding a series of yarns upon a spool, side arms pivotally connected to the frame for swinging movement for either of two positions and having seats to which a wound spool may be transferred, a guide bar secured to the pivotally mounted side arms between the seats and the winding means for movement with the side arms, a slide mounted upon the guide bar for bodily movement across the yarn sheet from one arm to the other in either position of the side arms, and motor operated shears carried by the slide to cut the yarn sheet in a straight line. 10
3. In a setting frame, the combination of winding mechanism for winding a series of yarns side by side upon a spool, side arms pivotally supported on the frame for movement to either of two positions and having seats to which a wound spool may be transferred, a guide bar extending between and secured to the side arms for movement therewith as the side arms are turned about their pivotal supports to either of said two positions, a slide mounted on the guide bar for movement lengthwise of said bar transversely across the setting frame, and motor driven shears connected 15
- to the slide for bodily movement therewith across the setting frame to cut the yarn sheet in either position of the side arms. 20
4. In a setting frame, the combination of means for winding a series of yarns side by side upon a spool, side arms movable to either of two positions and having seats to which a wound spool may be transferred that the yarn sheet may be positioned for cutting, a guide bar between the side arms and motor driven shears mounted upon and supported by the guide bar for movement transversely of the setting frame for cutting the yarn sheet in a straight line in either of the two positions of the side arms. 25
5. In a setting frame, the combination of means for winding a series of yarns side by side on a spool, side arms having seats for a wound spool and pivotally mounted for movement from a normally upright position to a substantially horizontal position, a guide bar between the side arms and motor driven cutting mechanism supported by the guide bar for movement transversely between the side arms to cut the yarn sheet of an "under" wound spool in a straight line while the side arms are in the normal upright position and to cut the yarn sheet of an "over" wound spool in a straight line when the side arms are in a substantially horizontal position. 30
